SMALLWARE LOOM

William Matterson, Coalville, England

Application April 4, 1939, Serial No. 265,975
In Great Britain April 5, 1938

14 Claims. (Cl. 139—138)

This invention relates to smallware looms such as are employed to produce ribbons and elastic webs. Looms of this type are adapted for simultaneously weaving a number of webs side by side and include a batten along which the shuttles are reciprocated by rack and pinion mechanism.

The invention, moreover, has reference particularly to a shuttle motion which excludes straps and comprises a part or member, e. g. a roller, which is formed or provided on a suitable part of, on or connected with the rack or racks and adapted for engagement with cam means having a cam formation designed to impart the desired reciprocatory motion to the shuttles and driven in suitable timed relation with the parts of the loom.

The object of the present invention is to provide in a loom of the character concerned a shuttle motion which is of the form just referred to but incorporates improvements designed to make it of a more simple and positive character and smoother and quieter in action than motions heretofore employed. Moreover, the aim is to provide a shuttle motion whereby the known disadvantages can be eliminated so that the loom can be readily run at high speeds with consequent increase in output and at the same time better results.

In the accompanying drawings,

Figure 1 is a front elevational view of so much of a smallware loom as is necessary to illustrate the application thereto of one form of the improved shuttle motion.

Figures 2 and 3 are rear and side elevational views of the same respectively.

Figure 4 is a detail transverse sectional view of the batten taken on the line IV—IV of Figure 1.

Figure 5 is a diagram representing the contour of the slot formed in the oscillatory cam lever of the mechanism.

Figure 6 is a view similar to Figure 3 illustrating a modified system of levers and connections for oscillating the said cam lever.

Figures 7 and 8 are detail rear elevational and plan views respectively showing an alternative manner of associating the cam lever with the rack and pinion mechanism whereby the pause or dwell between shuttle strokes can be readily varied as will be hereinafter described.

Like parts are designated by similar reference characters throughout the drawings.

In Figures 1, 2 and 3 of the drawings one end of the main frame of the loom is indicated at 1, the batten at 2 and 3 and 4 represent a pair

of racks which are disposed parallel to each other and arranged to reciprocate in the batten in the usual way. The existing crank shaft of the loom is shown at 5 and the batten 2 is operated from this shaft by means of connecting rods or links such as that indicated at 6 in Figure 3. In the example now being described the batten is adapted to swing back and forth, for which purpose it is supported, in known manner, by means of upwardly extending arms such as 7 which at their upper ends are pivotally mounted at the top of the loom so as to be capable of being oscillated. The racks when reciprocated serve to rotate pinions 8 carried by brackets 9 (Figure 1) each of which is adjustably secured to the front of the batten 2 and provided with a guideway or channel 10 to guide a shuttle in its movements back and forth through a shed of warps; the required movements of the shuttles (not shown) are obtained by reason of the co-operation of the pinions 8 with teeth on the shuttles, all in a manner now well known and familiar to those acquainted with the art concerned.

The shuttle motion is located at one end of the loom and the two racks 3 and 4 are rigidly connected with or attached to a slidable member 11 which carries at the back thereof a roller 12 adapted to engage in a slot 13 formed in a pivoted cam lever 14. At its upper and lower edges this slidable plate or member 11 is adapted to engage in and slide along channels or grooves 15 formed in the batten. These channels or grooves are formed by appropriately recessing the batten and securing strips 16 to the back of the latter in the manner shown more clearly in Figure 4. The strips 16 are so applied and secured in position as, in effect, to constitute retaining members for maintaining the racks 3 and 4 and the slid-able carrier member 11 in the batten. The said member is mounted so as to work within the con-fines of a rectangular opening 17 provided in the batten. At one end and at the back of the batten 2 is attached a plate 18 carrying a rearwardly projecting pivot pin 19 upon which the cam lever 14 is mounted. This lever is maintained in position upon the pivot by means of a split pin 20 and has formed at its free end an extension 14a in which the cam slot 13 is provided. The said extension, generally speaking, extends slightly obliquely with respect to the portion 14b of the lever and its shape is determined by the con-tour of the slot 13 therein. Conveniently the slot is S- or similarly shaped and comprises two sub-stantially straight end portions a and b and an intermediate curved portion c. Strengthening 55

ribs such as 21 and 22 and bosses or protuberances such as 23 and 24 are provided on the pivoted cam lever where considered necessary and the latter is designed so as to have no superfluous portions. The disposition, size and contour of the cam slot 13 may, however, vary widely according to the length of stroke of the shuttles and the speed at which the latter are to operate. The construction so far described is therefore such that when the cam lever 14 is oscillated on its pivot 19, the member 11 and hence also the racks 3 and 4 are reciprocated to operate the shuttles, by reason of the engagement of the roller 12 in the slot 13. With a cam slot of the representative contour shown in Figure 5 the movement of each shuttle, in making a complete stroke, begins slowly, increases and then diminishes. Moreover, the formation of the end portions *a* and *b* of the slot are designed to cause the shuttles to pause or dwell between strokes. The advantage of this is that the shuttles are passed quickly through the sheds but both before and after passing through the latter move slower so that there is ample time for changing the sheds after the shuttles have made one stroke and before they pass back through the sheds on the next stroke. This obviates slam and results in a smooth motion being obtained. In turn the smooth motion prevents the bobbins or quills of the shuttles from over-running at the ends of the shuttle strokes. Now, assuming the cam lever to be so positioned that the roller 12 is accommodated within the portion *a* of the slot 13 and thereby occupies the full line position indicated in Figure 5, then the member 11 and racks 3 and 4 are at rest. If now the cam lever is turned on its pivot and moved to such an extent in a downward direction that the roller becomes located in the portion *b* of the slot and occupies the position indicated at *e*, then during this movement of the lever, the member 11 and the racks will first be caused to move slowly (in a direction towards the right of Figure 1) during the time that the portion *c* of the slot passes over the roller, then more quickly by reason of the passage over the roller of the portion *c*² of the slot, after which the speed of movement will diminish gradually during engagement of the roller with the portion *c*³ of the slot until the parts are brought to rest. Conversely, if the cam lever is moved to the same extent in an upward direction, the movement of the member 11 and the racks will be correspondingly reversed, that is to say they will move in a direction from right to left (Figure 1), the movement commencing slowly, increasing and then diminishing until the racks are once again brought to rest prior to subsequent movement from left to right. It will be noted from a consideration of Figure 5 that the oscillation of the cam lever is such that the ends of the slot therein are not at any time brought into contact with the roller 12; this is to ensure that slam is prevented.

The cam lever 14 is adapted to be oscillated from the crank shaft 5. A gear wheel 25 is rigidly secured to the appropriate end of this shaft and adapted to mesh with a larger gear wheel 26 which is rotatably mounted in a suitable bearing 27 provided on the frame of the loom (see more particularly Figure 3). The ratio between these two gear wheels is 2/1 so that for each complete revolution of the crank shaft 5 the gear wheel 26 makes half a revolution. The last mentioned gear wheel carries a crank pin 28 to which the

lower end of a rod or link 29 is secured. This rod or link serves to connect the crank pin 28 with a sliding block 30 adapted to slide between fixed guideways or guides 31 provided in or on the frame 1. The guides 31 are bolted or otherwise attached to projecting U-shaped portions 32 formed on a bracket 33 which is bolted to one of the cross members 1a at the top of the loom frame. By slotting the cross member 1a the bracket 33 can be made adjustable. The opposite side edges of the block 30 are appropriately grooved for engagement with the guides. In turn the sliding block is connected with the cam lever 14 by means of another rod or link 34. Thus, when the crank shaft 5 rotates, the cam lever 14 is oscillated through the medium of the aforesaid gear wheels, the rods or links 29 and 34 and the sliding block 30, which latter is common to both rods or links. The said block is furnished with a projecting pin or stud 35 upon which the upper ends of the connecting rods or links are pivotally mounted and retained in position by a split pin 36 or any other suitable means. Similarly, the cam lever is provided with a pin or stud 37 upon which the lower end of the rod or link 34 is mounted. The last mentioned rod or link is made adjustable, for which purpose it is made in two portions each having a screw-threaded engagement with an intermediate coupling member 38 which is adjustable to vary the effective length of the rod or link and can be locked in any position to which it is adjusted by means of nuts 39.

An alternative arrangement of driving means for the cam lever—more particularly suitable for heavier types of looms—will now be described with reference to Figure 6. In this arrangement a radially extending slot 40 is formed in the gear wheel 26, which slot is adapted for reception of a crank pin 41 carried by a rod or link 42 serving to connect the said pin with an arm 43. This arm is pivotally mounted at 44 on the upper part of the main frame 1 and extends in a generally horizontal direction from the back towards the front of said frame. The said arm is spring-controlled, e. g. by one or more tension springs 45, and the arrangement is such that as the crank shaft 5 and hence also the inter-meshing gear wheels 25 and 26 revolve, the arm is moved up and down on its pivot 44 by the connecting rod or link 42, the degree of movement of the arm being determined by the throw of the crank pin 41. The throw of the pin is varied by adjusting it within the slot 40. If desired the opposite, i. e. upper, end of the rod or link 42 may, as shown, be connected in an adjustable manner with the pivoted arm 43. The forward end of the arm is connected with the cam lever 14 by means of another rod or link 46, so that as the crank shaft 5 revolves the cam lever is oscillated. The connection of the last mentioned rod or link with the arm 43 may, if desired, also be of an adjustable character, in addition to which the rod or link itself may be made adjustable in the manner shown. As will be understood, by adjusting the crank pin in the manner hereinbefore described the throw thereof is altered with the result that the timing of the pivoted cam lever is correspondingly changed to vary the dwell between strokes of the shuttles.

When a crank (such as that indicated at 47) on the crank shaft 5 is horizontally disposed and projects towards the rear of the loom, then the roller 12 should be so disposed in the cam slot 13 that all the shuttles are in the middle of a stroke.

Bearing this fact in mind it is possible accurately to trace out the contour of the cam slot before this is actually formed in the lever 14, by moving the crank shaft step by step to the extent of one tooth on the gear wheel secured to said shaft and determining the corresponding extent of movement of the roller which is necessary to give the desired movement of the shuttles. Some such method of tracing out the contour of the cam slot is necessary or desirable because, as will be appreciated, it is difficult or impossible to determine the contour theoretically since the movements and angularities of the various intermediate connections and their effect on the movement of the cam lever have to be taken into consideration.

In the modified construction shown in Figures 7 and 8, the roller 12, instead of being mounted directly on a part to which the rack or racks of the rack and pinion mechanism is or are rigidly secured, is mounted upon a pivoted lever 48 in turn connected with the said rack or racks by means of a link or lever 49. For the sake of convenience only one rack is shown in each of Figures 7 and 8, this being indicated by the reference numeral 3. Rigidly secured to the appropriate end of the rack is a part 50 which projects up through and works within a slot 51 formed in the batten 2. This part is itself slotted at 52 for reception of a pivot pin 53 upon which is mounted one end of the link or lever 49. By suitable adjustment of the pin 53 in the slot 52 the point of connection of the said link or lever with the part 50 can be varied within limits. At its opposite end the link or lever is pivotally mounted upon a pin or stud 54 which projects forwardly of the lever 48 near the upper end thereof and is adjustable within a slot 55 formed in the lever. The roller 12 engages the cam slot 13 and at its lower end the lever 48 is pivotally mounted upon a bracket 56 which is conveniently screw or otherwise secured to the underside of the batten. The construction is such that when the cam lever 14 is oscillated, oscillatory movement is also imparted to the lever 48—by reason of engagement of the roller thereon with the cam slot 13—which movement is transmitted to the part 50, and hence also to the rack 3, through the medium of the link or lever 49. It is claimed for this arrangement that by appropriate adjustment of one or both of the pivot pins 53 and 54 in the slots 52 and 55 respectively, the pause or dwell between shuttle strokes can be readily varied in a simple manner.

The cam lever embodied in the construction last described may be driven in either of the ways aforesaid.

An advantage (other than the advantages already mentioned) of the constructions herein described is that the shuttles can be moved through the sheds with a relatively small crank throw.

It will be understood that the invention is applicable to smallware looms of all kinds including looms with ordinary battens and looms with mock space battens, for making all kinds of narrow-ware such as ribbons, narrow elastic web and like smallware with advantageous results such as increased speed as compared with looms having shuttle motions including straps, absence of slap owing to the elimination of straps, which incidentally are also affected by atmospheric conditions, elimination of slamming and the production of a smoother shuttle action.

The invention is suitable for application to

looms with battens which have rectilinear backward and forward motion as for instance on slides or in guides as well as to looms with swinging battens. Moreover, the invention may advantageously be applied to needle looms for the purpose of moving the weft needles back and forth through the sheds.

What I claim then is:

1. In a smallware loom, in combination, a batten, a crank shaft from which said batten is operated, gearing driven from said shaft, shuttles which are movable to and fro along the batten, rack and pinion mechanism for reciprocating the shuttles, said mechanism comprising at least one rack which transmits motion to the shuttles through the medium of pinions, a part associated with said rack and pinion mechanism, a cam member which is pivotally mounted upon the batten and formed with a shaped guideway for reception of said part, and connecting rods for oscillating said cam member, one of said rods being connected with the aforesaid gearing and another with the cam member, for the purpose herein specified.

2. In a smallware loom, in combination, a batten, a crank shaft from which said batten is operated, gearing driven from said shaft, shuttles which are movable to and fro along the batten, rack and pinion mechanism for reciprocating the shuttles, said mechanism comprising at least one rack which transmits motion to the shuttles through the medium of pinions, a part associated with said rack and pinion mechanism, a cam member which is pivotally mounted upon the batten and formed with a shaped guideway for reception of said part, a sliding block, a connecting rod which is connected at one end with the aforesaid gearing and at the other end with said sliding block, and another connecting rod which serves to connect the cam member with the block whereby said cam member is oscillated to impart the desired reciprocatory motion to the shuttles.

3. In a smallware loom, in combination, a batten, a crank shaft from which said batten is operated, gearing driven from said shaft, shuttles which are movable to and fro along the batten, rack and pinion mechanism for reciprocating the shuttles, said mechanism comprising at least one rack which transmits motion to the shuttles through the medium of pinions, a part associated with said rack and pinion mechanism, a cam member which is pivotally mounted upon the batten and formed with a shaped guideway for reception of said part, a pivoted lever, a connecting rod which is connected at one end with the aforesaid gearing and at the other end with said pivoted lever, and another connecting rod which serves to connect the cam member with the pivoted lever whereby said cam member is oscillated to impart the desired reciprocatory motion to the shuttles.

4. In a smallware loom, in combination, a batten, shuttles which are movable to and fro along said batten, rack and pinion mechanism for reciprocating the shuttles, said mechanism comprising at least one rack slidable longitudinally of the batten and which transmits motion to the shuttles through the medium of pinions, a part connected to and which is movable with said rack, a cam member which is mounted upon the batten, said cam member being formed with a shaped guideway for reception of said part and arranged for movement first in one direction and then in the opposite direction, and means for operating

- said cam member whereby the desired reciprocatory motion is imparted to the shuttles.
5. In a smallware loom, in combination, a batten, shuttles which are movable to and fro along said batten, rack and pinion mechanism for reciprocating the shuttles, said mechanism comprising at least one rack slidable longitudinally of the batten and which transmits motion to the shuttles through the medium of pinions, a part connected to and which is movable with said rack, an oscillatory cam member which is movably mounted upon the batten and formed with a shaped guideway for reception of said part, and means for effecting oscillation of said cam member whereby the desired reciprocatory motion is imparted to the shuttles.
6. In a smallware loom, in combination, a batten, shuttles which are movable to and fro along said batten, rack and pinion mechanism for reciprocating the shuttles, said mechanism comprising at least one rack slidable longitudinally of the batten and which transmits motion to the shuttles through the medium of pinions, a part connected to and which is movable with said rack, an oscillatory member which is mounted upon the batten and has formed therein a cam slot for reception of said part, and means for operating said oscillatory member whereby the desired reciprocatory motion is imparted to the shuttles.
7. A combination according to claim 6, wherein the oscillatory member is in the form of a pivoted lever.
8. In a smallware loom, in combination, a batten, shuttles which are movable to and fro along said batten, rack and pinion mechanism for reciprocating the shuttles, said mechanism comprising at least one rack slidable longitudinally of the batten and which transmits motion to the shuttles through the medium of pinions, a part connected to and which is movable with said rack, a cam member which is movably mounted upon the batten, said cam member being formed with a shaped guideway for reception of said part and arranged for movement first in one direction and then in the opposite direction, and means for operating said cam member whereby the desired reciprocatory motion is imparted to the shuttles, said cam member being designed to impart reciprocatory motion to the shuttles at a variable speed and to cause said shuttles to pause or dwell between strokes.
9. A combination according to claim 8, wherein the cam member is designed to impart motion to the shuttles such that at each stroke of each of the latter the movement begins slowly, increases and then diminishes.
10. In a smallware loom, in combination, a batten, a crank shaft from which said batten is operated, shuttles which are movable to and fro along the batten, rack and pinion mechanism for reciprocating the shuttles, said mechanism comprising at least one rack slidable longitudinally of the batten and which transmits motion to the shuttles through the medium of pinions, a part connected to and which is movable with said rack, a cam member which is pivotally mounted upon the batten and formed with a shaped guideway for reception of said part, and means adapted to be operated from the aforesaid crank shaft for oscillating said cam member whereby the desired reciprocatory motion is imparted to the shuttles.
11. In a smallware loom, in combination, a batten, shuttles which are movable to and fro along said batten, rack and pinion mechanism for reciprocating the shuttles, said mechanism comprising at least one rack slidable longitudinally of the batten and which transmits motion to the shuttles through the medium of pinions, a part connected to and which is movable with said rack, a lever which is pivotally mounted on the batten and has at its free end an extension which is angularly disposed with respect to the remaining portion and has formed therein a substantially S-shaped cam slot for reception of the aforesaid part, and means for oscillating said lever whereby the desired reciprocatory motion is imparted to the shuttles.
12. In a smallware loom, in combination, a batten having guideways therein, shuttles which are movable to and fro along said batten, rack and pinion mechanism for reciprocating the shuttles, said mechanism comprising racks slidable longitudinally of the batten and which transmit motion to the shuttles through the medium of pinions, a part connected to and which is attached to the racks and adapted to slide between the aforesaid guideways in the batten, a roller on said part, a cam member which is movably mounted on the batten, said member being formed with a shaped guideway for reception of said roller and arranged for movement first in one direction and then in the opposite direction, and means for operating said cam member whereby the desired reciprocatory motion is imparted to the shuttles.
13. In a smallware loom, in combination, a batten, shuttles which are movable to and fro along said batten, rack and pinion mechanism for reciprocating the shuttles, said mechanism comprising at least one rack slidable longitudinally of the batten and which transmits motion to the shuttles through the medium of pinions, a pivoted lever which is connected with the rack, a roller on said lever, a cam member which is movably mounted on the batten, said member being formed with a shaped guideway for reception of said roller and arranged for movement first in one direction and then in the opposite direction, and means for operating said cam member whereby the desired reciprocatory motion is imparted to the shuttles.
14. In a smallware loom, in combination, a batten, shuttles which are movable to and fro along said batten, rack and pinion mechanism for reciprocating the shuttles, said mechanism comprising at least one rack slidable longitudinally of the batten and which transmits motion to the shuttles through the medium of pinions, a part movable with and secured to said rack, a pivoted lever, a link to which said lever is connected in an adjustable manner and which is in turn similarly connected to the aforesaid part secured to the rack, a roller on said lever, a cam member which is movably mounted on said batten, said cam member being formed with a shaped guideway for reception of said roller and arranged for movement first in one direction and then in the opposite direction, and means for operating the cam member whereby the desired reciprocatory motion is imparted to the shuttles.

WILLIAM MATTERSON.

70
